UNITED STATES PATENT OFFICE

2,564,469

VACUUM CLEANER

Gustaf E. Lofgren, Riverside, Conn., assignor to
 Electrolux Corporation, Old Greenwich, Conn.,
 a corporation of Delaware

Application February 25, 1946, Serial No. 649,929

20 Claims. (Cl. 183—37)

1

This invention relates to vacuum cleaners and is particularly concerned with means for disposing of dust, dirt, and like foreign matter which has been accumulated during cleaning operations. The present invention is also concerned with automatic control means responsive to certain operating characteristics of the device.

While certain aspects of the present inventive concept may be broadly applicable to a wide variety of types of vacuum cleaners, the invention is more particularly concerned with tank type vacuum cleaners in which a relatively stationary casing, housing a motor-fan unit and a removable dust collecting bag, is provided with an intake opening to which a suction hose is applied. Such devices are provided with suitable cleaning tools which may be selectively attached to the end of the hose and from such tools dust is drawn through the tube and deposited in the bag, the clean air being exhausted through the opposite end of the casing.

One of the outstanding problems presented by such cleaners is the removal and disposed of the dirt collected. Cleaners of this type now on the market provide for the removal of the front cover whereupon an open mouthed dust collecting bag is removed and the dust shaken from the bag which is thereafter returned for further cleaning operations. In addition to the obvious objection to such procedure because of the required cover manipulation and exposure of the collected dirt, it is frequently impossible for the operator to determine when the bag should be emptied. The collection of dirt by the bag causes the pores and interstices of the fabric to become clogged, thus reducing the flow of air therethrough and consequently reducing the efficiency and effectiveness of the cleaner. However, such reduction in efficiency may not be apparent to the operator and thus, since the emptying of the bag is the least pleasant of the cleaning operations, it is frequently postponed beyond the time when efficiency would best be served by emptying.

It is one of the primary objects of the present invention to provide a new and improved means for disposing of the accumulated dirt of a vacuum cleaner.

It is a further object of the invention to provide in a vacuum cleaner means responsive to accumulation of dust therein for actuating a dirt disposal means.

Another object of the present invention is to provide a vacuum cleaner of the general type herein referred to in which the dirt disposal may be accomplished without manual manipulation of

2

a front cover and/or without manipulation of the suction hose.

A further and important object of the invention is to provide for the accumulation of dust within the cleaner in a removable, disposable, and self-closing dust bag which may be safely handled after removal from the device without danger of scattering the contents or soiling the hands of the operator.

10 A still further and important object of the invention is to provide a vacuum cleaner which automatically in response to efficiency changes or at the discrimination of the operator will withdraw from the casing a sealed disposable dust

15 receptacle.

Other objects and features of the present invention will be apparent from the consideration of the following specification when taken in conjunction with the accompanying drawings in

20 which:

Fig. 1 is a side elevation partly broken away showing one embodiment of the present invention, and;

Fig. 2 is a similar view showing the device in 25 position for bag removal.

In general terms the structure of the present embodiment of the invention may be defined as including a substantially cylindrical, normally, horizontal body within which is mounted a

30 motor-fan unit for causing a flow of air from the front to the rear therethrough. Both ends of the body are formed for normally permanent rigid association with the body proper, the front end being provided with an air intake to which a 35 suction hose may be applied which hose is adapted to receive suitable cleaning tools, which the rear end adjacent to the motor-fan unit is provided with a suitable outlet for cleaned air. The top of the body forwardly of the motor-fan unit

40 is cut away to form an open topped chamber which is normally closed by a pivotally mounted top cover which is provided with means for receiving and securing a porous dust bag preferably of paper or like inexpensive and thus disposable

45 material. The arrangement is such that with the cover closed the bag mouth is positioned to receive from the front end, the dust laden air which is filtered by the porous material of the bag, the dirt being retained therein and the clean

50 air passing through the motor-fan unit to be exhausted at the rear end. When the dirt is to be disposed of, the top cover is lifted carrying with it the dust receptacle and presenting it for convenient disposal. The inventive concept also 55 embraces automatic means for raising the cover

as by a spring power storing mechanism which may be released in response to a variation in an operating characteristic of the device as for instance, a decrease in operating efficiency due to overcharging the bag with accumulated dirt.

Referring now to the drawings which depict a specific structural embodiment of one form of the invention, the horizontally disposed casing body is indicated by the numeral 10 midway of the casing there is provided an apertured bulkhead 11 behind which is mounted a motor-fan unit 12 and in the front of the bulkhead there is disposed an air filter 13. The casing body 10 is preferably supported on sleighs 14 and a manually controlled switch 15 is provided to control the motor-fan unit. The rear or exhaust end of the casing 10 is closed by a permanently mounted rear end plate 16 which is suitably apertured to permit the discharge of air therethrough and as in conventional practice, and may be provided with means for receiving the hose so that the device may be used as a blower. The forward end of the casing is likewise provided with a permanently secured front end plate 17 through which is mounted a hose receiving tube 18 to which the suction hose may be detachably secured.

The top of the body is cut away as at 19 from a point adjacent to the front end plate 17 and midway of the height of the body to a point at the top of the body adjacent to the bulkhead 11 and the casing is provided with a cover 20 supported on arms 21 pivotally secured to the body as at 22. At the rear or motor end of the cover 20 there is provided a downwardly extending apertured bag pressure plate 23 the lower end of which terminates in a forwardly extending bag supporting shelf 24. As will hereinafter be described, the pressure plate and supporting shelf act to lift the bag with the cover as the cover is raised. It is to be noted, however, that while the plate and shelf are sufficiently rigid to perform this operation, the plate is permitted to flex with respect to the cover in response to pressure applied by the end of the bag and such flexure acts upon an arm 25 pivotally mounted in the bottom of the casing as at 26 and which is normally retained in a vertical position against the lower portion of the pressure plate 23 by a spring indicated at 27. Upon such rear movement of the pressure plate, the arm 25 is pivotally moved rearwardly to contact and operate a switch 28 which is arranged to cut out the supply of power to the motor-fan unit and to release the cover to permit opening thereof in a manner hereinafter to be described.

As indicated at 29, a gasket is provided between the cover 20 and the open top of the body 10 to insure a tight seal therebetween when the cleaner is in operation.

The front end of the cover 20 is provided with a bag holding plate 30 which is centrally apertured and provided with an air inlet tube 32 which is adapted to register with and seal against a sealing gasket 33 mounted upon the inner extension 34 of the tube 18.

The dust collecting bag of the present form of the invention is identified by the numeral 35 and is of the type disclosed in the copending application of Leon P. Borkoski, Serial No. 641,992, filed January 18, 1946. The body of the bag is preferably made from inexpensive porous material such as paper, so that the bag may be disposed of whenever filled with dust without prohibitive expense. The front edges 36 of the body of the bag 35 are secured between inner

and outer end members 37 and 38, respectively, both of which are apertured to receive therethrough the air inlet tube 32 of the plate 30. A pair of normally overlapping rubber closure members 39 is stretched across the apertures of the end members, the arrangement being such that when the tube is inserted through the apertures the rubber closure members are separated and engage the tube to seal the bag thereto and to retain the bag thereon during cleaning operations. When the top cover is opened, the retention of the members 39 is effective to lift the bag out of the casing.

While the cover 20 may be manually manipulated by a handle 40, it is preferable to provide power means for raising it and this is accomplished by a spring 41 mounted at the pivot 22 in such manner that the cover is always biased to open position. To secure the cover in its normal closed position during operation of a cleaner, a latch 42 is provided which engages a latch opening 43 in the bottom of the lower portion of the bag holding plate 30. The latch 42 is provided with a forwardly extending trip arm 44 which extends through the front end plate 17 to permit manual tripping of the latch to release the cover, the latch being normally retained in cover engaging position by its spring 45. In order to provide automatic opening of the cover a solenoid 46 is mounted in the front end plate 17 and is adapted upon energization to rock the latch to cover releasing position. The circuit for the solenoid operates through the switch 28 so that as the bag fills with dirt and becomes less porous, its pressure on the plate 23 will cause the switch 28 to be operated cutting off the energization of the motor and releasing the cover which raises to the position shown in Fig. 2.

The operation of the device will be readily understood from a consideration of the foregoing. With the bag 35 in position on the inlet tube 32 and with the cover 20 closed as shown in Fig. 1, the operation of the motor-fan unit will cause dust laden air from the cleaning tool to be drawn through the end plate 17 and into the bag. The plate 30 and gasket 33 form an effective seal to prevent the passage of air around the bag. The porous characteristics of the bag acts to filter out the dirt and dust which is retained within the bag while the clean air passes out through the rear end plate 16. When it is desired to empty the bag or to inspect it, pressure as by the foot, is applied to the arm 44 of the latch 42 which releases the plate 30 permitting the cover to be raised by its handle 40 or by its spring 41. The cover then assumes the vertical position shown in Fig. 2 permitting the bag to be stripped from the inlet tube and discarded. A clean bag may then be applied to the tube and the cover closed for further operation. However, should the operator neglect to discard the bag when its efficiency has been reduced by clogging of the pores, the increased pressure difference will cause the bag to be forcibly drawn against the pressure plate 23 causing the arm 25 to actuate the switch 28 which will break the circuit to the motor and energize the solenoid 46 thereby releasing the latch and permitting the cover to open, by virtue of the cover spring, thus presenting the bag for disposal.

In carrying out the present invention, it will be understood that the concept is not limited to the specific structural embodiment thereof herein shown and that numerous changes and modifications may be resorted to without departure

from the spirit or scope of the invention as outlined in the appended claims.

What I claim is:

1. In a vacuum cleaner, a casing defining a dust bag compartment, said casing including a stationary wall, an inlet passage extending through said wall to said compartment, means for connecting a suction hose to the outer end of said passage, said casing being formed with an opening at one side of said compartment, a cover for said opening hinged to said casing, an inlet conduit carried by said cover and positioned so as to communicate with said inlet passage when said cover is closed, and a dust bag provided with an inlet opening engageable with said inlet conduit whereby said bag is withdrawn from said compartment through said opening when said cover is opened.

2. In a vacuum cleaner, a casing defining a dust bag compartment, said casing including a stationary wall, an inlet passage extending through said wall to said compartment, means for connecting a suction hose to the outer end of said passage, said casing being formed with an opening at one side of said compartment, a cover for said opening hinged to said casing, an inlet conduit carried by said cover and positioned so as to communicate with said inlet passage when said cover is closed, means for biasing said cover towards open position, latching means for retaining said cover in closed position, a dust bag provided with an inlet opening at one end thereof engageable with said inlet conduit, and a bag supporting member secured to and movable with said cover and engageable with the opposite end of said bag, whereby the bag is withdrawn from said compartment through said opening when said cover is opened.

3. In a vacuum cleaner, a casing defining a dust bag compartment having an opening at one side thereof, a cover for said opening hinged to said casing, means for biasing said cover towards open position, latching means for retaining said cover in closed position, a dust bag, means including a resilient member carried by said cover and engageable by said bag, means for producing flow of air through said bag, said resilient member being displaceable in response to increasing force exerted thereagainst by said bag resulting from increasing pressure drop of air passing through the bag, and means responsive to displacement of said resilient member for releasing said latching means, whereby said cover is opened by the biasing means and said bag is carried with the cover out of said compartment.

4. In an air filtering machine of the type comprising a filter compartment including an opening and closing member adapted to be opened for the insertion and removal of a filter, a mechanism normally tending to open said member, releasable means for holding said member in its closed position against the action of said mechanism during normal operation of said machine, an electrical relay operable to release said releasable means, and a switch operable in response to a predetermined filled condition of said filter for actuating said relay to permit opening of said member when said filter becomes filled with filtered material to a predetermined degree.

5. In a vacuum cleaner of the type comprising a filter compartment including an opening and closing member adapted to be opened for the insertion and removal of a filter, a mechanism normally tending to bias said member to its open position, releasable latch means for holding said

member in its closed position against the biasing force of said mechanism during normal operation of said machine, an electrical relay operable to release said latch means, and a switch operable in response to a predetermined filled condition of said filter for actuating said relay when said filter becomes filled with filtered material to a predetermined degree.

6. In a vacuum cleaner, a housing having an air inlet opening, means for producing flow of air into said housing through said inlet, a dust separating member in said housing in the path of air flow between said inlet and said means, a cover on said housing providing access to said dust separating member, supporting structure for said dust separating member mounted on said cover for movement therewith, resilient means carried by said cover and engageable by said dust separating member, said resilient means being movable in response to an increase in pressure drop through said dust separating member, and means actuatable in response to a predetermined movement of said resilient member for moving said cover and dust separating member outwardly with respect to said housing.

7. In a vacuum cleaner, a housing having an air inlet opening, means for producing flow of air into said housing through said inlet, a dust separating member in said housing in the path of air flow between said inlet and said means, a cover on said housing providing access to said dust separating member, supporting structure for said dust separating member mounted on said cover for movement therewith and including resilient means carried by said cover and engageable by said dust separating member, said resilient means being movable in response to an increase in pressure drop through said dust separating member, and means actuatable in response to a predetermined movement of said resilient member for moving said cover and dust separating member outwardly with respect to said housing.

8. In a vacuum cleaner, a housing having an air inlet opening, means for producing flow of air into said housing through said inlet, a dust separating member in said housing in the path of air flow between said inlet and said means, a cover on said housing biased to open position and providing access to said dust separating member, latch means retaining said cover in closed position, supporting structure for said dust separating member mounted on said cover for movement therewith, resilient means carried by said cover and engageable by said dust separating member, said resilient means being movable in response to an increase in pressure drop through said dust separating member, said latch means being actuatable in response to a predetermined movement of said resilient member for releasing said cover and moving said dust separating member outwardly with respect to said housing.

9. In a vacuum cleaner, a housing having an air inlet opening, means for producing flow of air into said housing through said inlet, a dust separating member in said housing in the path of air flow between said inlet and said means, and access opening in said housing providing access to said dust separating member, supporting structure at least partially enclosing said dust separating member and mounted for movement outwardly with respect to said housing, and means actuatable in response to a predetermined pressure drop through said dust separating member for moving said dust separating member outwardly with respect to said housing.

10. In a vacuum cleaner, a housing defining a dust bag compartment, said housing including a fixed wall, an air inlet passage extending through said wall to said compartment, said housing being formed with an access opening to said compartment, means for producing flow of air into said housing through said inlet passage, a dust bag removably positioned in said compartment in the path of air flow between said inlet and said means, means operable for moving said dust bag outwardly through said access opening, and means responsive to an increase in pressure drop through said dust bag for actuating said means operable for moving said dust bag.

11. In a vacuum cleaner, a housing defining a dust bag compartment, said housing including a fixed wall, an air inlet passage extending through said wall to said compartment, said housing being formed with an access opening to said compartment, means for producing flow of air into said housing through said inlet passage, a dust bag removably positioned in said compartment in the path of air flow between said inlet and said means, means operable for moving said dust bag outwardly through said access opening, said means operable for moving said dust bag comprising a closure member for said access opening having means for engaging and supporting said dust bag, and means responsive to an increase in pressure drop through said dust bag for actuating said means operable for moving said dust bag.

12. In a vacuum cleaner, a housing defining a dust bag compartment, said housing including a fixed wall, an air inlet passage extending through said wall to said compartment, said housing being formed with an access opening to said compartment, means for producing flow of air into said housing through said inlet passage, a dust bag removably positioned in said compartment in the path of air flow between said inlet and said means, an air inlet opening in said dust bag communicating with said air inlet passage, means operable for moving said dust bag outwardly through said access opening, and means responsive to an increase in pressure drop through said dust bag for actuating said means operable for moving said dust bag.

13. In a vacuum cleaner, a housing defining a dust bag compartment, said housing including a fixed wall, an air inlet passage extending through said wall to said compartment, said housing being formed with an access opening to said compartment, means for producing flow of air into said housing through said inlet passage, a dust bag removably positioned in said compartment in the path of air flow between said inlet and said means, an air inlet conduit extending into said dust bag and engageable with said air inlet passage, means operable for moving said dust bag outwardly through said access opening, said means operable for moving said dust bag comprising a closure member for said access opening having means for engaging and supporting said dust bag, and means responsive to an increase in pressure drop through said dust bag for actuating said means operable for moving said dust bag.

14. In a vacuum cleaner, a housing defining a dust bag compartment, said housing including a fixed wall, an air inlet passage extending through said wall to said compartment, said housing being formed with an access opening to said compartment, means for producing flow of air into said housing through said inlet passage, a dust bag removably positioned in said compartment

5 in the path of air flow between said inlet and said means, means operable for moving said dust bag outwardly through said access opening, said means operable for moving said dust bag comprising a closure member for said access opening having means for engaging and supporting said dust bag, and means including an electric circuit responsive to an increase in pressure drop through said dust bag for actuating said means operable for moving said dust bag.

15. In a vacuum cleaner, a rigid casing having an opening, a dust bag removably mounted in said opening, a cover member connected to said casing and having an air inlet tube for communicating with the interior of said dust bag, means for opening said member, a latch to hold said member closed, an electrically energizable device to release said latch, an electrical control circuit therefor, and means responsive to predetermined increase in pressure drop through said bag to energize said control circuit and thereby said device to release said latch.

16. In a vacuum cleaner, a rigid casing having an opening, a dust bag removably mounted in said opening, a cover member connected to said casing and having an air inlet tube for communicating with the interior of said dust bag, means for opening said member, a latch to hold said member closed, an electrically energizable device to release said latch, an electrically energizable motor driven fan within said casing to draw air through said tube and bag, and electrical control means responsive to a predetermined increase in pressure drop through said bag to energize said device to release said latch and to interrupt the circuit to said motor.

17. In a vacuum cleaner, a rigid casing having an opening, a dust bag removably mounted in said opening, a cover member connected to said casing and having an air inlet tube for communicating with the interior of said dust bag, means for opening said member, a releasable latch to hold said member closed, means operable to release said latch, means including a solenoid adapted upon energization to effect operation of said latch releasing means, an electrically energizable motor driven fan within said casing to draw air through said tube and bag, and electric control means responsive to predetermined increase in pressure drop through said bag to energize said solenoid to release said latch and to interrupt the circuit to said motor.

18. In a vacuum cleaner, a rigid casing having an opening, a dust bag removably mounted in said opening, a cover member connected to said casing and having an air inlet tube for communicating with the interior of said dust bag, means for opening said member, means carried by said member for moving said bag outwardly when said member is opened, a latch to hold said member closed, an electrically energizable device to release said latch, an electrical control circuit therefor, and means responsive to predetermined increase in pressure drop through said bag to energize said control circuit and thereby said device to release said latch.

19. In a vacuum cleaner, a rigid casing having an opening, a dust bag removably mounted in said opening, a cover member connected to said casing and having an air inlet tube communicating with the interior of said dust bag and being closable to hold said bag in said casing, a latch to hold said member closed, an electrically energizable device to release said latch,

an electrically energizable motor driven fan within said casing to draw air through said tube and bag, an electric switch in the circuits to said device and motor, and means responsive to an increase in pressure drop through said 5 dust bag to actuate said switch to energize said latch and deenergize said motor.

20. In a vacuum cleaner, a casing having an opening, a motor fan unit for producing flow of air through said casing, means for supplying energy to said motor, a dust receiving container receivable within said casing, means for moving said container outwardly, means for restraining said moving means, means actuatable to release said restraining means, and control 10 means including an electric circuit operable to actuate said last-mentioned means and to interrupt the supply of energy to said motor fan unit, said control means being operable in response to an increase in pressure drop through 15 said container.
